(57) **CLAIM**

We claim the ornamental design for a pull tab for a slide fastener, as shown and described herein.

DESCRIPTION

FIG. 1 is a front view illustrating the pull tab for a slide fastener;

FIG. 2 is a bottom view of the pull tab;

FIG. 3 is a top view of the pull tab;

FIG. 4 is a right side view of the pull tab;

FIG. 5 is a left side view of the pull tab;

FIG. 6 is a right side section view of the pull tab taken along line 6—6 of FIG. 1; and,

FIG. 7 is a front view showing the pull tab of FIG. 1 in connection with a slide fastener slider body for illustrative purposes only and forms no part of the claimed design.
